UNITED STATES PATENT OFFICE.

ALLEN T. DORSEY, OF ST. LOUIS, MISSOURI.

CLOTH-PACKAGE.

1,031,252.

Specification of Letters Patent.

Patented July 2, 1912.

Application filed April 26, 1911. Serial No. 623,357.

To all whom it may concern:

Be it known that I, ALLEN T. DORSEY, a citizen of the United States, residing at the city of St. Louis, State of Missouri, have invented a certain new and useful Cloth-Package, of which the following is such a full, clear, and exact description as will enable any one skilled in the art to which it appertains to make and use the same, reference being had to the accompanying drawings, forming part of this specification.

My invention relates to a cloth package and more particularly to one in which the bolt of goods while being thoroughly protected, at the same time can be readily inspected and in which access may be had to the body of the bolt of goods for severing a portion therefrom.

In the accompanying drawings which illustrate one form of cloth package made in accordance with my invention, Figure 1 is a cross section; Fig. 2 is a perspective view; Fig. 3 is a perspective view of one end of the package, the display portion of the goods being folded on the main portion, and Fig. 4 is a plan view on a reduced scale of the blank from which the envelop is formed.

Like marks of reference refer to similar parts in the several views in the drawings.

The bolt of goods is arranged in two parts, namely a main part 5 and a display part 6. In folding the bolt of goods I do not fold the goods longitudinally so as to bring the selvage edges together but on the contrary allow the creases to be only across the goods so that each layer or fold of the goods displays the entire width of the goods thus forming what is usually known as a long fold. In order to protect both the main or body portion 5 and the display portion 6 of the goods I provide a two-part envelop which is preferably formed from a blank like that shown in Fig. 4. In this envelop the part which protects the display portion 6 of the goods consists of two sections of the envelop designated 7 and 8 and end-flaps 9. The other portion of the envelop which protects the body 5 of the goods is formed integral with the above described part and consists of the sections 10 and 11, the latter having an extended edge 12 which is adapted to be folded under the body of the goods 5 as best shown in Figs. 1 and 2. The section 10 is provided

with end-flaps 13 adapted to protect the ends of the body 5. In order to secure the end-flaps 13 to the section 11 I preferably provide the section 11 with staples 14 and the flaps 13 with openings 15 adapted to receive the prongs of said staples. When, however, the package is to be used only in the retail trade this fastening device may be omitted.

In using my package the portion of the envelop consisting of the sections 7 and 8 and containing the display portion of the bolt of goods is folded over the main portion, as shown in Fig. 3. The goods is thus entirely protected from soiling or other injury. When it is desired to display the goods the display portion is folded down in to the same plane with the main portion, as shown in Figs. 1 and 2. The goods may thus be readily inspected while at the same time the main or body portion 5 is still thoroughly protected. When it is desired to remove a portion of the goods the end-flaps 13 are folded down, as shown at the lower portion of Fig. 2, the edge 12 is pulled out from under the body portion of the goods and the section 11 is folded back, as shown in Fig. 4. Access is thus readily had to the body portion of the goods for removing any desired length therefrom in the usual way, and the only part of the bolt exposed to injury by soiling is the relatively small display portion 6.

Having fully described my invention, what I claim as new and desire to secure by Letters Patent of the United States, is:

1. In a cloth package, the combination with a bolt of cloth arranged in long fold and comprising a body portion and a relatively smaller display portion, whereby said body portion presents an inner edge adjacent to said display portion, of a two-part envelop, one part of said envelop being adapted to receive and completely envelop the body portion including said inner edge, and the other part being adapted to receive the display portion.

2. In a cloth package, the combination with a bolt of cloth arranged in long fold and comprising a body portion and a display portion, of a two-part envelop one part of said envelop comprising the sections 7 and 8 and the end-flaps 9 and receiving the display portion of the goods, and the other part of said envelop comprising the sections 10 and 11, the underfolded edge 12 and end-

flaps 13 and receiving the body portion of the goods.

3. In a cloth package, the combination with a bolt of cloth arranged in long fold 5 and comprising a body portion and a display portion, of a two-part envelop, one part of said envelop comprising the sections 7 and 8 and the end-flaps 9 and receiving the display portion of the goods, the other part of 10 said envelop comprising the sections 10 and 11, underfolded edge 12, and end-flaps 13,

and receiving the body portion of the goods, and fastening means for securing the end-flaps 13 to the sheet 11.

In testimony whereof, I have hereunto set 15 my hand and affixed my seal in the presence of the two subscribing witnesses.

ALLEN T. DORSEY. [L. S.]
